UNITED STATES PATENT OFFICE.

KARL C. RANDALL, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CIRCUIT BREAKER.

Application filed June 30, 1921. Serial No. 481,546.

To all whom it may concern:

Be it known that I, KARL C. RANDALL, a citizen of the United States, and a resident of Edgewood Park, in the county of Allegheny and State of Pennsylvania, have invented a new and useful Improvement in Circuit Breakers, of which the following is a specification.

My invention relates to switch mechanism and particularly to circuit breakers of the enclosed type.

One object of my invention is to provide an enclosed circuit breaker and disconnecting switch wherein means are provided for preventing the operation thereof except in the proper sequence.

Another object of my invention is to provide an enclosed switch mechanism wherein the covers for preventing access to the circuit breaker and to the disconnecting switch are so interlocked with the disconnecting switch that they cannot be opened so long as the disconnecting switch remains in closed position.

Another object of my invention is to provide a switch mechanism, having the above characteristics, wherein the disconnecting switch and the controller for the circuit breaker are locked in predetermined positions by means of key-actuated devices, and wherein a single key is employed for separately actuating both devices and wherein removal of the key from either device is prevented except when the device, that is in operative relation to the key, is in a predetermined position, thereby insuring a proper sequence of operation.

These and other objects, that will be made apparent throughout the further description of the invention, are attained by means of the enclosed circuit-breaker apparatus hereinafter described, and illustrated in the accompanying drawings, wherein:

Figure 1 is a semi-diagrammatic view of the switch mechanism, showing the housing in cross-section and the various elements of the mechanism in side elevation;

Figs. 2 and 3 are semi-diagrammatic views of the circuit-breaker controlling mechanism, showing various positions of the controller;

Figs. 4 and 5 are side elevational views, on an enlarged scale, of the disconnecting-

switch-operating mechanism, showing various positions of the operating handle; and

Figs. 6 and 7 are front and end views, respectively, of the housing.

Referring to the drawings, the apparatus includes a housing 9 that is divided into a disconnecting-switch compartment 11 and a circuit-breaker compartment 12 by means of a partition 10. The compartments 11 and 12 are provided with hinged covers 13 and 14, respectively, the former being hinged to the side of the housing by means of hinges 15, and the latter being hinged to the opposite side thereof by means of hinges 16.

The circuit breaker, which may be of any preferred type, includes a pair of stationary contact members 18 and 19 that are bridged by a movable switch member 21 which is provided with an operating rod 22. The contact members 18 and 19 and the bridging member 21 are submerged in oil, which is contained within a tank 23 that is mounted within the circuit-breaker compartment 12. The bridging member 21 is actuated, through a system of rods and levers, by means of an electromagnet 24, the armature of which is pivoted to a lever 25 which turns about the pivot 26. One arm of the lever 25 is connected to a lever 27 by means of a connecting rod 28, and one arm of the lever 27 is connected, by means of a link 29, to a lever 31 that is pivotally attached to the upper end of the switch rod 22.

When the armature 30 of the electromagnet is actuated, the connecting rod 28 is moved downwardly to impart an upward movement to the bridging member 21 through the medium of the levers 27 and 31. The switch is retained in closed position by means of a latch 32 that is pivoted to the housing by means of a shaft 33. This latch member is provided with a projection 34 that engages the underside of the free end of the lever 25 to retain it in closed position.

The latch 32 is actuated by an electromagnetic trip coil 35, the armature 36 thereof being pivotally connected to the latch 32 by means of a pivot pin 37. When the coil 35 is energized, the latch 32 is moved toward the left and the lever 25 is released, thereby causing the switch member 21 to

fall away from the contact members 18 and 19 by the force of gravity. A spring may be employed to cause the switch to move to open position with a snap action.

5 The current through the circuit-breaker-actuating coil 24 and the trip coil 35 is controlled by means of a control switch, which is illustrated semi-diagrammatically in Figs. 1, 2 and 3. The control switch comprises a circular disc 39 that rotates about a shaft 41. The disc 39 is provided with an operating handle 42 and its edge is provided with a notch 43, the purpose of which will hereinafter appear. A contact member 44 is attached to, and moves with, the disc 39 and operatively engages stationary contact terminals 45, 46 and 47.

10 The contact number 44 may be moved to the two operative positions illustrated in Figs. 1 and 3 and to the inoperative positions illustrated in Fig. 2. When the contact member 44 is in the position illustrated in Fig. 1, the trip coil 35 is energized by a circuit from the feed conductors 48 and 49 through the conductor 51, the terminal 46, the switch member 44, the terminal 45, the conductor 52, the switch 53, the conductor 54, the coil 35 and the conductor 55 which is connected to the feed conductor 49. As 15 illustrated, the circuit breaker and the operating mechanism therefor are in the open position which they occupy immediately after the trip coil 35 has been energized.

20 In order to close the circuit breaker, the coil 24 is energized by turning the disc 39 until the switch member 44 connects the contact terminals 46 and 47. This causes a circuit to be established through the coil 30 from the feed conductor 48, through the conductor 51, the contact terminal 46, the contact member 44, the terminal 47, the conductor 56, the coil 24 and the conductor 55, to the feed conductor 49.

25 In order to interrupt the circuit through the control switch 44 when the control switch is in the tripping position, illustrated in Fig. 1, the switch 53, which is attached to the lever 25, is provided in the circuit 54 through the trip coil 35. When the switch 30 of the circuit breaker is moved to open position, the switch 53 is disengaged from the contact members 57. Consequently, no current will flow through the trip coil after the circuit breaker has been tripped.

35 Separate disconnecting switches 58 and 59 are provided for the conductors 61 and 62 that are connected to the circuit-breaker terminals 18 and 19, respectively. The disconnecting switches may be of any preferred form and severally comprise a pivot jaw member 63 and a switch jaw member 64, said members being mounted upon insulating pedestals 65. Switch-blade members 58a and 59a are pivoted to the pivot-jaw members 64,

40 The switch-blade members 58a and 59a are connected in tandem and are simultaneously actuated by means of an operating lever 66 which is pivoted at 67 to a link 68 and to a connecting rod 69. The lower end of the 45 rod 69 is pivotally connected to a link 71 that is pivoted to the switch-blade member 59. The rod 69 and the link 71 are pivoted to a bell-crank lever 72, one arm of which is pivotally connected to a locking rod 73 which extends through the partition 10 and the side wall 70 of the housing.

45 A latch member 75 is secured to the ends of the rod 73 exteriorly of the housing and, when the disconnecting switch is in closed 50 position, the latch 75 is disposed in the path of movement of the cover 14 and, therefore, prevents opening movement thereof so long as the switch is in closed position. When the disconnecting switch is moved to open 55 position, the latch 75 is moved outwardly to the position indicated in dotted lines in Fig. 7 and permits opening movement of the cover 14.

50 The operating lever 66 is pivoted to the housing by means of a shaft 76 and is provided, at its free end, with a handle 77 having a latch member 78 thereon. A bracket 79 is secured to the side of the housing and supports a key-actuated lock 81.

55 The operating handle 77 and the bracket 79 project through an opening 80 in the cover 13 and, when the handle 77 is in the closed position indicated in Fig. 1, it extends above the opening 80 and serves to prevent opening movement of the cover so long as the disconnecting switch is in closed position. When the handle is in the open 60 position illustrated in Fig. 5, the handle is in such a position that it will clear the opening and permit opening movement of the cover. By means of this arrangement and the latch 75, both the covers 13 and 14 are locked in closed position so long as the disconnecting switches are in closed position. Therefore, access can not be had to the circuit breaker mechanism or to the disconnecting switch mechanism unless the disconnecting switches are open.

65 The lock 81 is similar to the lock 82, illustrated in Figs. 1, 2 and 3, which comprises a housing 84 in which the lock bolt 85 is mounted for reciprocation thereon. The bolt is provided with a notch 86 for the purpose of receiving the wing 87 of the key 88. When the bolt is in the locking position illustrated in Fig. 1, the wing 87 of the key may be so turned that it will register with the narrow portion of the key-hole 89. The key may be withdrawn from the lock only when the bar 85 is in locking position. As shown in Fig. 1, the controller switch 44 is in tripping position wherein the circuit through the trip coil 35 is closed. In order to move the controller

switch 44 to the neutral position illustrated in Fig. 2 and to the closed position illustrated in Fig. 3, the key 88 must be inserted in the lock and the locking bar moved to its inner position in opposition to the compression spring 91. When the bar 85 has cleared the notch 43, the disconnecting switch 39 may be rotated. When the controller switch 44 is in any other position than the tripping position, the bar 85 cannot be moved to locking position and the key 88 cannot be removed for the reason that the shoulder 92 of the bar will not permit rotation of the key to a position in which it may be removed from the lock.

As previously stated, the lock 81 is of similar construction and the key 88 is adapted for actuating both the lock 81 and the lock 82. The operating handle 77 is retained in closed position by means of the lock bolt 93 of the lock 81 which engages the latch 78 and prevents movement thereof.

The handle 77 is locked in open position by means of the lock bolt 93 which enters the notch 94 in the latch 78. The key 88 can be withdrawn from the lock 81 only when the handle is in either full-open position or full-closed position. If the handle is in intermediate position, the lock bolt 93 cannot be moved to locking position and, consequently, the key cannot be removed from the lock, for, at this time, the shoulder 95 of the bolt 93 prevents rotation of the key to a position in which it may be removed from the lock.

It is an object of this invention to prevent the opening of the disconnecting switch while the circuit breaker is closed and to prevent the closing of the circuit breaker except when the disconnecting switch is in full-open position or full-closed position. If the disconnecting switch were closed while the circuit breaker is closed, it might result in the burning or destruction of the disconnecting switch and possible injury to the operator.

Assuming that the disconnecting switch and the circuit breaker are in closed position, the key will be in the lock 82 and cannot be removed for the purpose of unlocking the disconnecting switch until the controller switch 44 has been moved to tripping position. The key may then be turned to lock the controller switch in tripping position and may then be removed for the purpose of unlocking the disconnecting switch. After the disconnecting switch is unlocked and moved to full-open position, the key may be removed for the purpose of unlocking the controller switch. The locks may be of any preferred construction wherein a special key is required in order to permit of rotation thereof within the lock. It will be obvious from the foregoing that the key may not be removed from the lock 82 ex-

cept when the controller is in tripping position and the circuit breaker open. It is, therefore, impossible to unlock the disconnecting switch for movement either to open or to closed position when the circuit breaker is closed because the key 88 cannot be removed from the controller lock.

While I have described and illustrated but one embodiment of my invention, it will be apparent to those skilled in the art that various changes, modifications, substitutions, additions and omissions may be made in the apparatus illustrated without departing from the spirit and scope of the invention, as set forth in the appended claims.

I claim as my invention:

1. Switch mechanism comprising a circuit breaker, a disconnecting switch, a controller for the circuit breaker, means for locking the disconnecting switch in closed position, a locking means for the controller and means for actuating both of said locking means so interlocked with the controller that the actuating means is rendered inoperative to actuate the disconnecting-switch locking means while the controller is in a predetermined position.

2. Switch mechanism comprising a circuit breaker, a disconnecting switch, a controller for the circuit breaker, means for locking the disconnecting switch in closed position, a locking means for the controller and means for actuating both of said locking means so interlocked with the disconnecting switch locking means that the actuating means is rendered inoperative to actuate the controller while the disconnecting-switch locking means is in a predetermined position.

3. Switch mechanism comprising a circuit breaker, a disconnecting switch, controlling means, a key-actuated lock for the controlling means, a key-actuated lock for locking the disconnecting switch in closed position, a key for actuating the said locks and means in the lock for the controlling means for preventing removal of the key therefrom except when the controller is in a predetermined position.

4. Switch mechanism comprising a circuit breaker, a disconnecting switch, controlling means, a key-actuated lock for the controlling means, a key-actuated lock for locking the disconnecting switch in closed position, a key for actuating the said locks and means in the lock for the controller for preventing removal of the key therefrom except when the controller is in releasing position.

5. Switch mechanism comprising a circuit breaker, a disconnecting switch, controlling means, a key-actuated lock for the controlling means, a key-actuated lock for locking the disconnecting switch in closed position, a key for actuating the said locks and means in the lock for the disconnect-

- ing switch for preventing removal of the key therefrom except when the disconnecting switch is in predetermined positions. 35
6. Switch mechanism comprising a circuit breaker, a disconnecting switch, controlling means, a key-actuated lock for the controlling means, a key-actuated lock for locking the disconnecting switch in closed position, a key for actuating the said locks and means in the lock for the disconnecting switch for preventing removal of the key therefrom except when the disconnecting switch is in full-open or full-closed position. 40
7. Switch mechanism comprising a circuit breaker, a disconnecting switch, a key-controlled means for locking the disconnecting switch in a predetermined position, a key-controlled means for controlling the circuit breaker, a key for separately actuating both of the said key-controlling means, and separate means for preventing the removal of the key from either key-controlled means except when the key-controlled means that is in operative relation with the key is in a predetermined position. 45
8. Switch mechanism comprising a housing, a circuit breaker within the housing, a disconnecting switch within the housing for the circuit breaker, a movable cover for the housing, an operating handle for the disconnecting switch projecting through the cover and for preventing opening movement of the cover so long as the switch is in closed position and a key-controlled means for locking the handle in closed position. 50
9. Switch mechanism comprising a housing having two compartments, a cover for each compartment, a disconnecting switch in one compartment, a circuit breaker in the other compartment, a key-controlled means 40 for locking the covers in closed position when the disconnecting switch is in closed position, a second key-controlled means for controlling the circuit breaker, a key for separately actuating both of said key-controlled means and means for preventing the removal of the key from the second key-controlled means except when the latter is in a predetermined position. 55
10. Switch mechanism comprising a housing, a disconnecting switch within the housing, a movable cover for the housing, an operating handle for the disconnecting switch projecting through the cover and for preventing opening movement of the cover so long as the switch is in closed position and a key-controlled means for locking the handle in closed position. 50

In testimony whereof, I have hereunto subscribed my name this 22nd day of June 1921. 60

KARL C. RANDALL.
